CARBURETOR

John W. Fitz Gerald, Milwaukee, Wis., assignor
to Briggs & Stratton Corporation, Milwaukee,
Wis., a corporation of Delaware

Application July 13, 1935, Serial No. 31,245

18 Claims. (Cl. 123—119)

This invention relates to improvements in carburetors and refers more particularly to means for automatically controlling the choke valve of a carburetor.

5 It is an object of this invention to provide a choke control whereby the choke valve is automatically closed upon opening of the throttle valve to a starting position and is opened a degree determinate upon the thermal conditions 10 of the engine upon the starting of the engine.

Another object of this invention resides in the provision of means for controlling the functioning of an automatic choke control by the flow of 15 electric current incidental to the starting of the engine.

20 A further object of this invention is to provide a choke control of the character described wherein an electro-responsive element serves both as a means for releasing a mechanical latch between the choke valve and its actuator and for controlling the functioning of a thermally responsive latch likewise governing the connection between the choke valve and its actuator.

With the above and other objects in view which 25 will appear as the description proceeds, this invention resides in the novel construction, combination and arrangement of parts substantially as hereinafter described and more particularly defined by the appended claims, it being understood that such changes in the precise embodiment of the hereindisclosed invention may be 30 made as come within the scope of the claims.

The accompanying drawings illustrate one complete example of the physical embodiment of the 35 invention constructed according to the best mode so far devised for the practical application of the principles thereof, and in which:

40 Figure 1 is a side view of a carburetor showing the application of this invention thereto, parts of the mechanism being shown in section;

Figure 2 is an enlarged side view of the carburetor and the choke control mechanism with the parts in a position other than that shown in Figure 1;

45 Figure 3 is a detail section view taken through Figure 2 on the plane of the line 3—3; and

Figure 4 is a view similar to Figure 2 but showing the parts in still another position of adjustment.

50 Referring now more particularly to the accompanying drawings in which like numerals indicate like parts throughout the several views, the numeral 5 designates a carburetor having a mixing chamber 6 connectible with the manifold 7 of an internal combustion engine, an air inlet

8, and a float chamber 9. Fuel is conducted to the float chamber through a line 10 in the conventional manner and the fuel-air mixture passes into the manifold 7 as determined by the adjustment of a throttle valve 11. The admission of air is controlled by a choke valve 12 which, like the throttle valve, is of the conventional butterfly type.

The throttle valve is actuated from an accelerator (not shown) by means of a link 13 connected to an arm 14 fixed to the shaft 15 of the throttle valve. Also fixed to the shaft 15 is a lever 16 which is connected with the short arm 17 of a bell crank lever 18 pivoted as at 19 to the body of the carburetor, through a separable connection indicated generally by the numeral 20. The long arm 21 of the bell crank lever 18 is connected through a link 22 with a lever 23 fixed to the shaft 24 of the choke valve 12. A torsion spring 25 yieldingly maintains the choke 20 valve open.

The separable connection 20 comprises two rods 26 and 27 connected respectively to the levers 16 and 17. Secured to the rod 26 is a solenoid 28 having a hollow core in which the outer end 29 of the rod 27 is slidably disposed. The rod 27 is reduced in diameter as at 30 to provide a shoulder 31 with which a latch 32 engages to hold the rods 26 and 27 against separation. The latch 32 is in the form of an angularly bent strip mounted at 30 its upper end by a spring strip 33 secured to the core of the electromagnet in such position that its lower arm 34 moves across the lower end of the solenoid.

This lower horizontal arm 34 has a keyhole slot 35 in which the reduced portion 30 of the rod 27 is disposed. With the latch 32 in its normal position shown in Figure 1, the small end of the keyhole slot 35 is engaged with the rod 27 so that the arm 34 is disposed under the shoulder 31 to hold the rods 26 and 27 connected. Upon energization of the solenoid 28 the latch 32 being of magnetic metal moves to align the large end of the keyhole slot with the rod 27 thus releasing the same for movement away from the rod 26.

Energization of the solenoid 28 is effected by current from the generator of the engine with which the carburetor is used so that as the engine starts to operate under its own power and the generator begins to function, the latch holding the two sections or rods 26 and 27 of the separable connection 20 together is released to permit opening of the choke valve 12 regardless of the position of the throttle valve 11.

However, the degree of opening of the choke 55

valve 12 is controlled by a thermal latch indicated generally by the numeral 36. This latch comprises a stepped flange 37 fixed on the rod 27 and a bimetallic finger 38 fixed to the solenoid 28. In thermal relationship thereto to be influenced thermally by the solenoid. As the temperature at the bimetallic strip or finger 38 rises, its lower end which engages the stepped flange 37 moves outwardly to allow a step by step variation in the relative positions of the choke valve and throttle valve until the bimetallic finger moves outwardly sufficiently far to entirely disengage the flange 37 whereupon the choke valve 12 moves to its fully open position and remains there regardless of variations in the position of the throttle valve. To produce the heat necessary to influence the bimetallic holding finger 38, the solenoid 28 is preferably wound with resistance wire.

Operation

Assuming that the motor is cold, the ignition off and the throttle is in its idling position, as shown in Figure 1, the choke valve is then fully open, the latch 32 is closed and likewise the thermal latch is in position engaging the lowermost step on the flange 31. During starting of the engine, the throttle valve is advanced to a partially open position which movement carries the choke valve by reason of the connection 20 to its fully closed position against the action of its spring 25. As the engine starts and sufficient current is generated by its generator, the solenoid becomes energized and attracts the latch 32 to release the rod 27 for movement away from the rod 26.

40 However, inasmuch as the thermal latch 36 is in position engaging the lowermost step on the flange 37, the choke valve remains in its closed position.

40 As the engine begins to operate normally and the temperature at the thermal latch 36 rises, the choke valve is gradually permitted to open, assuming that the throttle valve remains in its position shown. In this condition of the engine 45 that is, before it is warmed up to its normal running temperature, if the throttle is suddenly advanced unless some means of enriching the fuel supply is provided, the engine misses and often ceases to operate entirely.

With the present invention this objectionable condition is entirely obviated and if the engine is accelerated during this period, the further opening of the throttle valve returns the choke valve to its closed position thereby enriching the fuel-air mixture.

The response of the thermal latch 36 is such that it requires a predetermined time and a predetermined temperature rise before it is entirely disengaged from the flange 36 and until this period of time has elapsed, the choke valve remains connected with the throttle valve to be closed or at least moved toward closed position upon opening of the throttle valve. At the end of this period of time, the thermal latch 36 moves to its position in Figure 4 to entirely disengage the flange 37 and permit the choke valve to move to its fully open position and to remain there regardless of subsequent adjustment of the throttle valve.

70 Obviously, upon stopping of the engine the connection 20 will be re-established automatically by the closing of the throttle valve which lowers the latch to its position at which it engages under the shoulder 31.

From the foregoing description taken in connection with the accompanying drawings, it will be readily apparent to those skilled in the art to which this invention appertains, that this invention provides a novel and simple manner of automatically controlling the position of the choke valve in a carburetor and coordinating its functioning with the adjustment of the throttle valve during the starting cycle of the engine. 5

What I claim as my invention is:

1. In a carburetor, the combination of a choke valve biased to open position, a manually controlled throttle valve, a connection between the throttle valve and choke valve for translating an opening movement of the throttle valve into a 15 closing movement of the choke valve, said connection being separable to free the valves from each other, and automatically operable means for breaking the connection between the valves.

2. In a carburetor, the combination of a choke valve biased to open position, a manually controlled throttle valve, a connection between the valves whereby movement of the throttle valve toward open position moves the choke valve toward closed position, electro-responsive means for breaking the connection between the valves, and thermally responsive means for delaying complete breakage of the connection between the valves. 20

25

3. In a carburetor, the combination of a choke valve biased to open position, a manually controlled throttle valve, a multiple connection between the valves whereby movement of the throttle valve toward open position moves the choke valve toward closed position, electro-responsive means for breaking one of said connections, and thermally responsive means for controlling the other connection whereby complete breakage of the connection between the valves requires a predetermined temperature rise at said thermal means. 40

4. In a carburetor, the combination of a choke valve biased to open position, a throttle valve, and a connection between the valves whereby the valves are held in definite relative positions and whereby motion of one valve is positively translated into corresponding motion of the other valve, said connection being adjustable as to length in accordance with temperature changes thereat. 45

5. In a carburetor, the combination of a choke valve biased to open position, a throttle valve, means for adjusting the throttle valve, and a thermally controlled connection between the valves operable to maintain the valves connected in different relative positions so that movement of the throttle valve toward open position moves the choke valve toward closed position different degrees until a predetermined temperature is attained at said thermal means whereupon the connection between the valves is entirely disrupted. 55 60

6. In a carburetor, the combination of a choke valve biased to open position, a throttle valve, means for opening and closing the throttle valve, a connection between the valves comprising a part movable with the throttle valve, another part movable with the choke valve, a thermal latch carried by one part, and a stepped abutment carried by the other part and with which the thermal latch engages to maintain the valves connected in different relative positions dependent upon the temperature at said thermal latch. 70

7. In a carburetor, the combination of a choke valve biased to open position, a throttle valve, means for opening and closing the throttle valve, 75

- a connection between the valves comprising a part movable with the throttle valve, another part movable with the choke valve, a mechanical latch connecting said parts to maintain a fixed 5 relative relationship between the valves, means for releasing said mechanical latch to allow separation of said parts, and means coordinated with the temperature rise in an engine with which the carburetor is used for controlling the rate of 10 separation of said parts.
8. In a carburetor, the combination of a choke valve biased to open position, a throttle valve, means to open and close the throttle valve, a connection between the valves comprising a part 15 movable with the throttle valve, a part movable with the choke valve, a mechanical latch carried by one part and engageable with an abutment on the other part to hold the valves in definite fixed relative positions with respect to each other, 20 electro-responsive means for disabling the mechanical latch, and a thermal latch operable to hold the valves in different predetermined relative positions with respect to each other and to completely disconnect the valves from each other 25 upon a predetermined temperature rise at said thermal latch.
9. In a carburetor, the combination of a choke valve biased to open position, a throttle valve, means to open and close the throttle valve, a connection between the valves comprising two 30 latches, and means for quickly releasing one latch and for slowly releasing the other latch.
10. In a carburetor, the combination of a choke valve biased to open position, a throttle valve, means for opening and closing the throttle valve, means for connecting the valves so that movement of the throttle valve toward open position effects movement of the choke valve towards 35 closed position, said connection comprising rapidly acting and slowly acting latches, and means controlled by some function of an engine with which the carburetor is used for releasing said latches.
11. In a carburetor for internal combustion engines having an electrical system including a generator, the combination of a choke valve biased to open position, a throttle valve, means for adjusting the throttle valve, a connection 40 between the valves so that movement of the throttle valve toward open position moves the choke valve toward closed position, said connection comprising quick acting and slow acting latches, and common electro-responsive means energized from the generator of the engine for releasing 45 said latches.
12. In a carburetor for internal combustion engines having an electrical system including a generator, the combination of a choke valve biased to open position, a throttle valve, means for adjusting the throttle valve, a connection 50 between the valves comprising a mechanical latch, electro-responsive means controlled by the generator of the engine for releasing the mechanical latch, and thermally responsive means providing an auxiliary latch and operable to hold the valves connected at different relative positions with respect to each other until a predetermined temperature rise has been attained 55 at said thermal means.
13. In a carburetor for internal combustion engines having an electrical system including a generator adapted to generate current during normal operation of the engine, the combination of a choke valve biased to open position, 60
- a throttle valve, means for adjusting the throttle valve, a separable connection between the valves whereby movement of the throttle valve toward open position moves the choke valve toward closed position, said connection comprising a 65 mechanical latch adapted to hold the valves in fixed relative positions, electro-responsive means energized from the generator for releasing the mechanical latch and a thermal latch augmenting the mechanical latch and adapted to gradually permit disconnection of the choke valve from the throttle valve in step with the temperature rise at said thermal latch.
14. In a carburetor, the combination of a choke valve biased to open position, a manually controlled throttle valve, a connection between the valves whereby movement of the throttle valve toward open position moves the choke valve toward closed position, electro-responsive means for breaking the connection between the valves, 20 and thermally responsive means to change the length of the connection between the valves and thereby their degree of opening.
15. In a carburetor for internal combustion engines, the combination of a choke valve, a 25 throttle valve, a two-part link including a connecting latch engageable when the throttle valve is completely closed to connect the valves, magnetic means operable by the running of the engine to prevent engagement of the latch if the 30 engine is running and to disengage said latch upon starting of the engine, and a second connecting latch responsive to ambient thermal conditions to permit gradual lengthening of the link.
16. In a carburetor, the combination of a choke 35 valve biased to open position, a throttle valve, means for opening and closing the throttle valve, means for connecting the valves so that movement of the throttle valve toward open position effects movement of the choke valve towards 40 closed position, said connection comprising rapidly acting latch and slowly acting length adjusting devices, and means controlled by some function of an engine with which the carburetor is used for successively releasing said rapidly acting 45 latch and the slowly acting length adjusting devices.
17. In a carburetor for internal combustion engines having an electrical system including a generator, the combination of a choke valve 50 biased to open position, a throttle valve, means for adjusting the throttle valve, a connection between the valves so that movement of the throttle valve toward open position moves the choke valve toward closed position, said connection comprising rapidly acting latch and slowly 55 acting length adjusting devices, and means controlled by some function of the engine for successively releasing the rapidly acting latch and the slowly acting length adjusting devices.
18. In a carburetor for internal combustion engines, the combination of a choke valve biased to open position, a throttle valve, a connection 60 adjustable as to length between said valves for holding them in definite relative positions, and means for predetermining the length of said connection, said means being responsive to and operable in accordance with ambient temperature changes as effected by engine temperature so that the length of the connection and consequently the relative positions of the valves is 65 controlled by engine temperature.
- 70

JOHN W. FITZ GERALD.
